(57) CLAIM

The ornamental design for a measuring tool of body size, as shown and described.

DESCRIPTION

FIG. 1 is a top front perspective view of a measurement tool of body size of my present invention.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is an bottom plan view thereof.

Statement: Portions not illustrated form no part of the claimed design. No claim is made to the inner portions of the inventions or disclaimed portions demarcated by dash-dash disclaim lines. The surface shading lines illustrate contour only and form no part of the present design. The dash-dash disclaim lines indicate portions which form no part of the claimed design.
